CHRONOGRAPH

Egbert VanHaaften, Closter, N.J., assignor to Bulova Watch Company, Inc., New York, N.Y.

Filed Nov. 20, 1969, Ser. No. 20,203

Term of patent 14 years

Int. Cl. D10—02

U.S. Cl. D42—8

FIG. 1 is a perspective view of a chronograph showing my new design;

FIG. 2 is an enlarged scale top plan view;

FIG. 3 is a right side elevational view thereof;

FIG. 4 is a left side elevational view; and

FIG. 5 is a front elevational view.

The characteristic feature of my design resides in the particularly shaped operating levers in association with the generally triangular flanges.

I claim:

The ornamental design for a chronograph, substantially as shown and described.
